DESIGN FOR AN ILLUMINABLE RULE

Roland K. Olson, Newton, Mass.

Application April 25, 1947, Serial No. 138,605

Term of patent 3½ years

(Cl. D74—1)

To all whom it may concern:

Be it known that I, Roland K. Olson, a citizen of the United States, residing at Newton, county of Middlesex, and Commonwealth of Massachusetts, have invented a new, original, and ornamental Design for an Illuminable Rule, of which the following is a specification, reference being had to the accompanying drawings, forming a part thereof.

In the accompanying drawings Fig. 1 is a top plan view, Fig. 2 is a view in side elevation, and Fig. 3 is a perspective view of an illuminable rule, showing my new design.

I claim:

The ornamental design for an illuminable rule, substantially as shown.

ROLAND K. OLSON.
